(57) **CLAIM**

The ornamental design for the resealable steam bag, as shown and described.

DESCRIPTION

FIG. 1 is a perspective view of an embodiment of a resealable steam bag in a closed state;

FIG. 2 is a top view thereof;

FIG. 3 is a bottom view thereof;

FIG. 4 is a first side view thereof;

FIG. 5 is a second side view thereof;

FIG. 6 is a third side view thereof;

FIG. 7 is a fourth side view thereof;

FIG. 8 is a perspective view of the resealable steam bag in an open state;

FIG. 9 is a top view thereof;

FIG. 10 is a bottom view thereof;

FIG. 11 is a first side view thereof;

FIG. 12 is a second side view thereof;

FIG. 13 is a third side view thereof; and,

FIG. 14 is a fourth side view thereof.

The broken line showing of portions of the resealable steam bag is included for the purpose of illustrating environmental structure and forms no part of the claimed design.
